UNITED STATES PATENT OFFICE.

CHARLES M. HEETER, OF BUTLER, PENNSYLVANIA.

OIL-WELL PACKER.

1,423,213.

Specification of Letters Patent. Patented July 18, 1922.

Application filed September 26, 1918. Serial No. 255,764.

To all whom it may concern:

Be it known that I, CHARLES M. HEETER, a citizen of the United States, residing at Butler, in the county of Butler and State 5 of Pennsylvania, have invented a new and useful Improvement in Oil-Well Packers, of which the following is a full, clear, and exact description, reference being had to the accompanying drawings, forming part 10 of this specification, in which—

Figure 1 is a side elevation of my improved packer.

Figure 2 is a vertical section on the line II—II of Figure 1, showing the packer in 15 the well in the position in which it is to be used.

Figure 3 is a view similar to Figure 2, showing the device in the position it assumes when the first holding device has gone 20 into operation.

Figure 4 is a view similar to Figure 3 in which both holding devices have been moved into holding position with relation to the wall of the well.

25 Figure 5 is a similar view showing the packer in position within the well, and

Figure 6 is a perspective view of the lower end of the tube illustrating a portion of the latching member.

30 This invention relates to an improvement in oil well packers, and it is designed to provide an inexpensive and efficient packer having two holding devices which are brought into action before the packer is 25 set to avoid any danger of the packer shifting due to the giving way of the wall.

I am aware that it is old to use packers having two holding devices for engaging the wall, and in which the second holding 40 device is brought into action after the other holding device gives way. In my improved packer both holding devices are set before the packer is set, so that both holding devices are brought into action at almost the 45 same time when the packer is placed in the well. By this arrangement I am enabled to provide a holding device in which each holding device only supports a part of the load.

50 The precise nature of my invention will be best understood by reference to the accompanying drawings, which will now be described, it being premised, however, that various changes may be made in the details 55 of construction and the general arrangement of the parts without departing from the

spirit and scope of my invention as defined in the appended claims.

In the drawings the reference character 2 designates a tube which, in this case, extends throughout the entire length of the packer. Connected to the lower end of the tube by means of a pin 3 is a flanged member 4 having a recess or cut-away portion 5. Slidably mounted on the tube 2 above 60 the flanged member 4, is a combined slip and holding member 6. This slip and holding member comprises a ring at the lower end having four spring fingers 7 extending upwardly therefrom, and connected with the 70 upper end of each of these fingers 7 is a holding member 8, which is arranged to engage the wall of the well when the fingers are spread as hereinafter described. Connected to each of the fingers 7 is a frictional 75 spring member 9, and 10 is a hook member arranged to engage the flange 4^a to hold the slip and holding member in position when the device is lowered into the well. 11 is a frusto-conical member connected to the 80 tube 2 by means of a frangible pin 12. This frusto-conical member is arranged to engage frusto-conical surfaces on the holding members 8 to force them outwardly into 85 engagement with the wall of the well to support the tubing above the packer, as hereinafter described. Formed integrally with the frusto-conical member 11, or connected to the tube 2 by means of the frangible pin 13, is a second slip and holding member 14. 90 This slip and holding member is also provided with spring fingers 15, each having holding members 16 on the end thereof. 17 is a second frusto-conical member connected to the tube 2 by means of a frangible pin 95 18 and is arranged to force the holding members 16 against the wall of the well to assist in supporting the tubing as herein-after described. The upper end of the frusto-conical member is recessed for the 100 reception of a cylindrical flexible packing member 19 which is made of rubber or any suitable material. 20 is an expander for the flexible packing member 19 which may either be formed integrally with the tube 2 105 or connected thereto in any desired manner. In the drawings this expander is connected by means of a pin or screw 21. Connected to the upper end of the tubing is a compressor 23, which is arranged to form an 110 abutment or expander for the upper end of the packing member 19 to hold the upper

portion thereof in contact with the wall of the well. The compressor may be used for expanding the packing member without using the member 20, and which compressor 5 is threaded for the reception of the oil pipe 24 extending from the packer to the top of the wall.

The packer is set in the following manner: The parts are placed in the position shown 10 in Figures 1 and 2 and the tubing is connected to the compressor 23 and the device is lowered into the well, care being taken that the tubing is not rotated during the lowering of the packer. As soon as the packer has 15 been lowered to the point at which it is to be anchored, the tubing, as well as the packer, are rotated counter-clockwise with relation to the slip and holding member 6. The slip and holding member 6 is frictionally held against rotation by means of the 20 frictional springs 9, and when the hook member 10 engages the other side of the pin 3, the entire packer is lowered with relation to the holding member 6, to the position 25 shown in Figure 3. The frusto-conical member 11 will now expand the fingers 7. As soon as the frictional engagement between the members 11 and 8 is sufficient to prevent further downward movement of the 30 tube 2, the pin 12 will be sheared to permit the tubing 2 to move relative to the frusto-conical member 11. This shearing of the pin 12 will also cause the pin 13 to be sheared if the slip and holding member 14 is connected 35 to the tube 2 by means of a frangible pin. This shearing of the pin 12 will permit the tube 2 and the frusto-conical member 17 to move relative to the slip and holding member 14 and the frusto-conical member 17 will 40 expand the fingers 15 and move the holding members 16 into contact with the wall of the well as shown in Figure 4. When the downward movement of the frusto-conical member 17 is arrested, the pin 18 will be sheared 45 by the weight of the tubing above the packer and the weight of the tubing will force the expander 20 into the packing member 19 to expand the packing member 19 against the wall of the well, and if the expander is 50 moved a sufficient distance into the packing member 19 by the weight of the tubing, the compressor 23 will engage the top of the packing member and compress it so as to force it against the wall of the well. It will, 55 therefore, be readily appreciated that before the packing member 19 is expanded by means of this expander 20, both of the holding members 6 and 14 are wedged into contact with the wall of the well, so that the 60 tubing and packer are supported by two holding devices, and if one of the holding devices is in engagement with a portion of the wall which is liable to give way, the other holding device would be sufficient to 65 support the load.

The advantages of my invention result from the provision of a packer having two holding devices which simultaneously act to support the packer and the tubing above the packer.

70

I claim:

1. A well packer having an expansible packing member and a plurality of holding members below said packing member in different horizontal planes arranged to support 75 the packing member, a tube carrying the packing member and holding members and means frangibly connected to said tube for moving both of said holding members to operative position before the packing member is expanded, substantially as described.

2. A well packer having a flexible packing member, a tube carrying the same, an expander for said packing member, a plurality of holding members below the packing 80 member arranged to be brought into action before the expander operates on the packing member, and means frangibly connected to said tube for bringing the holding members into the desired operation, substantially as 85 described.

3. A well packer having a tube, an expander connected thereto, a flexible packing member adapted to move relative to the tube when the packer is set, a holding member 95 adapted to engage the wall of the well below said packing member, an expander for the holding member below the packing member and above the holding member, a slip and holding member below the first holding member, an expander between the slip and holding member and the first mentioned holding member, frangible connections between said expanders and the tube arranged to be broken before the expander for the 100 packing member is brought into action, and a latching device between the tube and the last mentioned slip and holding member; substantially as described.

4. A well packer comprising a tube adapted to be connected to an oil pipe, a flanged member having a recess connected to the lower end of the tube, a slip and holding member above said flanged member, a hook member connecting the slip and holding member to the flanged member, arranged to be released therefrom when rotated with relation thereto, said holding member having a plurality of expanding fingers having holding members on the upper ends thereof, 115 a frusto-conical member above said fingers connected to the tube by a frangible connection and arranged to move the holding members into contact with the wall of the well, a second holding member, a second frusto-conical member connected to the tube of the packer by means of a frangible connection, 120 said frusto-conical member being arranged to expand the fingers of the second holding member into contact with the wall of the 125 member. 130

- well, a flexible packing member surrounding the tube above the second frusto-conical member, and an expander for the packing member on the tube arranged to be brought 5 into action to expand the packing member after the second frusto-conical member has been disconnected from the tube, the arrangement being such that both holding devices are brought into action before the packing member is set; substantially as described.
5. A well packer comprising a tube adapted to be connected to an oil pipe, a flanged member having a recess connected to the lower end of the tube, a slip and holding member above said flanged member, a detachable hook member connecting the slip and holding member to the flanged member, said holding member having a plurality of expanding fingers having holding members on 15 the upper ends thereof, a frusto-conical member above said fingers connected to the tube by a frangible connection and arranged to move the holding members in contact with the wall of the well, a second holding member, a second frusto-conical member connected to the tube of the packer by means of a frangible connection, said frusto-conical member being arranged to expand the fingers of the second holding member into 20 the wall of the well, a flexible packing member surrounding the tube above the second frusto-conical member, an expander for the packing member on the tube arranged to be brought into action to 25 contact with the wall of the well, a flexible packing member surrounding the tube above the second frusto-conical member, an expander for the packing member on the tube arranged to be brought into action to 30 expand the packing member after the second frusto-conical member has been disconnected from the tube, and a compressor above the expander for the top of the packing member, the arrangement being such 35 that both holding devices are brought into action before the packing member is set; substantially as described.
6. A well packer having a tube, an expander connected thereto, a flexible packing member adapted to move relative to the tube when the packer is set, a holding member adapted to engage the wall of the well below said packing member, an expander for the holding member below the packing mem- 40 ber and above the holding member, a slip and holding member below the first holding member, an expander between the slip and holding member and the first mentioned holding member, frangible connections between said expanders and the tube arranged 45 to be broken before the expander for the packing member is brought into action, and a holding device between the tube and the last mentioned slip and holding member adapted to be released upon predetermined 50 rotation of said tube; substantially as described.
7. A well packer having an expansible packing member, a tube carrying the same, a holding member on said tube, means for 55 maintaining said holding member in inoperative position, said means being rendered ineffective upon rotating said tube relatively thereto in a predetermined direction, a second holding member, and means frangibly 60 connected to said tube for operating said second holding member after the operation of said first mentioned holding member and before the expansion of said packing member, substantially as described. 75
8. A well packer having a packing member, a tube carrying the same, a holding member on said tube, a second holding member on said tube and means frangibly 70 connected to said tube for operating both 80 of said holding members before expanding said packing, substantially as described.
9. A well packer having a packing member, a tube carrying the same, a holding member on said tube, a second holding member on said tube, means for operating one 85 of said holding members, means effective after the operation of said holding member for operating the second holding member, and means effective after the operation of 90 both of said holding members for expanding said packing, all of said means having frangible connection with the tube, substantially as described.

In testimony whereof, I have hereunto set 95 my hand.

CHARLES M. HEETER.
